CLAIM

The ornamental design for a combination aquarium and terrarium, as shown and described.

DESCRIPTION

FIG. 1 is a top perspective view of a combination aquarium and terrarium showing my new design;
FIG. 2 is an elevational view taken from the left end of FIG. 1;
FIG. 3 is a side elevational view thereof, the opposite side being a mirror image of the side shown; and
FIG. 4 is a top plan view thereof.
